CLAIM

The ornamental design for a mobile phone as shown and described.

DESCRIPTION

FIG. 1 is a front view of a mobile phone shown in a first embodiment;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a front perspective view thereof;

FIG. 8 is a rear perspective view thereof;

FIG. 9 is a front view of the mobile phone shown in a second embodiment;

FIG. 10 is a back view thereof;

FIG. 11 is a left view thereof;

FIG. 12 is a right view thereof;

FIG. 13 is a top view thereof;

FIG. 14 is a bottom view thereof;

FIG. 15 is a front perspective view thereof; and,

FIG. 16 is a rear perspective view thereof.

The broken lines depict portions of the mobile phone that form no part of the claimed design.
